ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,393,397.

Specification of Letters Patent. Patented Oct. 11, 1921.

Application filed February 2, 1920. Serial No. 355,573.

To all whom it may concern:

Be it known that I, ALONZO E. RHOADES, a citizen of the United States, residing at Hopedale, county of Worcester, State of Massachusetts, have invented an Improvement in Feeler Mechanism for Looms, of which the following description, in connection with the accompanying drawing, is a specification, like characters on the drawing 10 representing like parts.

This invention relates to an automatic filling replenishing loom such as the well known "Northrop" loom and has for its object to provide a simple and improved means 15 for detecting substantial exhaustion of filling and for effecting the initiation of filling replenishment.

This and other objects and features of the invention will appear more fully from 20 the accompanying description and drawings and will be particularly pointed out in the claims.

The drawings disclose so much of an automatic filling replenishing loom of the 25 Northrop type as is necessary to a disclosure of the invention together with a preferred form of the invention embodied therein.

Figure 1 is a plan view of a portion of the loom sufficient for a disclosure of the invention.

Fig. 2 is a side elevation looking toward the left in Fig. 1 of the feeler stand and parts mounted therein with a bobbin shown in cross section.

Fig. 3 is a view in vertical cross section of the construction shown in Fig. 2.

Fig. 4 is a top plan view partially broken away of the construction shown in Fig. 2.

Fig. 5 is a view in vertical cross section of 40 a portion of the construction taken on the line 5—5 of Fig. 1.

As the Northrop type of automatic filling replenishing loom is well known and familiar to those skilled in the art no extended 45 description of its construction or operation is here necessary.

The loom frame comprising the loom sides 1 and 2 connected by the breast beam 3 supports at the right a hopper stand 4 carrying 50 the usual rotary hopper in which are mounted the supply of fresh filling carriers. From this hopper upon the call for filling replenishment the fresh filling carriers are successively transferred by the action of the trans- 55 ferrer arm 5 to the shuttle then boxed in the

shuttle box 6 at the right hand side of the lay 7 and beneath the hopper.

The breast beam is also shown as supporting a weft fork 8 which receives its actuation from the usual constantly vibrating weft hammer 9 actuated from a shaft in the loom frame. The breast beam also supports the usual knock off lever 10 by which the shipper 11 is thrown to stop the actuation of the loom.

The initiation of the filling replenishing action of the loom is usually effected by a partial rotation of the controller rod or shaft 12 extending along the front of the loom beneath the breast beam. For this purpose the controller rod 12 is provided with an up-standing arm 13 to which is pivoted at 14 a latch 15, and the action is such that when the latch 15 is moved forwardly the controller rod 12 will be rocked to effect the 70 actuation of the transerrer 5 and thus effect the transfer of a fresh filling carrier from the hopper to the shuttle containing the exhausted filling carrier.

The detection of substantial filling exhaustion in the running shuttle is usually effected at the left hand side of the loom by a feeler mechanism so constructed and arranged that the point of the feeler upon the beat up enters through aligned openings in 85 the shuttle box and shuttle wall and feels against the mass of filling on the bobbin. When this mass of filling has become exhausted to a predetermined extent the feeler is so actuated or positioned as upon detection of this fact to set in motion the operation of the controller rod 12 to initiate the filling replenishing action.

The objects of the present invention are embodied in a preferred form of feeler 95 mechanism illustrated. In this construction the feeler stand 16 is secured as usual by a set screw 17 passing through a slot 18 therein to the breast beam at the left hand end of the loom. This feeler stand is a two 100 part box like structure secured together by the screws 19. A feeler head 20 preferably of rectangular cross section at its rearward end and terminating forwardly in a rod 21 is mounted for longitudinal movement in 105 the feeler stand. A helical spring 22 on the rod 21 serves to project the feeler head rearwardly and this rearward movement is limited by a projection 23 on the feeler head 110 engaging the feeler stand. The feeler head

is provided with a plurality of ways arranged in a vertical series to support and guide a corresponding plurality of feeler points or fingers and these ways are closed at one side to permit access to the feeler points and to retain them in place by a plate 24 removably secured to the feeler head as by the pins 25.

Each feeler point preferably is constituted as a flat horizontally arranged blade like member. In the construction shown there are three of these feeler points located in three ways arranged one above the other. The middle feeler point 26 is provided at its forward end with a butt 27 fitting in an enlarged section of its way and seated against a helical spring 28. The upper feeler point 29 and the lower feeler point 30 are shown as somewhat shorter than the middle 20 feeler point and the butts thereof 31 and 32 respectively extend in opposite directions from the body of the feeler point, but are located in similar enlarged portions of the ways and abut against similar springs 33 and 34. This arrangement of the butts of the feeler points enables the feeler points to be located quite closely together and the extreme rearward ends of the feeler points may be brought still more closely together 30 by bending the upper and lower feeler points toward the middle feeler point as shown in Figs. 2 and 3. A closing plate 35 is removably secured over the forward ends of the ways beneath the plate 24. Each feeler point is provided with a lateral projection 36 and these projections are located at the same distance from the rearward ends of the feeler points so that normally they stand in vertical alinement.

40 The bobbin 37 is formed near its butt to present a plurality of longitudinal grooves or recesses 38 supported by ribs 39. The arrangement is such that upon the beat-up the feeler points enter through the opening 45 40 in the shuttle box and the corresponding alined opening in the shuttle wall and contact with the mass of filling 41 on the bobbin. Preferably when this contact takes place the middle feeler point 36 is opposite the axis of the bobbin. So long as the grooves or recesses 38 are covered by the filling all of the feeler points will be pressed forwardly against their springs 28, 33 and 34 thus carrying the projections 36 forwardly. When, however, the filling has become exhausted to a predetermined degree 50 so as to uncover the grooves or recesses opposite the feeler points one or more of the feeler points will enter the oppositely disposed recess or groove and upon the completion of the beat-up will not be moved forwardly.

60 The idea of the plurality of vertically disposed feeler points is, and the arrangement is such, that no matter what may be

the angular axial position of the bobbin in the shuttle at least one of the feeler points will enter a recess in the bobbin when the filling is absent. It is impossible to position the bobbin rotarily in such a manner as 70 to prevent one of these feeler points entering a recess when it is uncovered. This is important because it is difficult if not impossible to secure a predetermined rotary or axial position of the bobbin in the shuttle. 75

The detecting action of the feeler caused by the failure of one or more of the feeler points to move forwardly when the filling has become exhausted sufficiently to uncover the grooves or recesses opposite the feeler points is availed of to initiate the filling replenishing action of the loom. This is secured through mechanism of a novel character, a preferred form of which is illustrated. 80

85 One of the novel features resides in the controlling mechanism being actuated by a vibrating member such as the vibrating weft hammer to position the means for initiating the filling replenishing action of the loom 90 in position to receive its actuation in turn from this vibrating member or weft hammer.

95 In the construction illustrated a rod 42 is mounted at one end in a bearing 43 on the 95 feeler stand and near the opposite end in a bearing 44 on a bracket 45 secured to the breast beam. The right hand end of this rod is offset to form a crank arm 46 which extends beneath the latch 15. Thus, the 100 rod 42 may be rocked in its bearings to raise the rearward end of the latch into position to receive actuation from the vibrating member or weft hammer 9. For this purpose the upper end of the weft hammer is 105 conveniently provided with a shouldered flange 47 against which the rearward end of the latch 15 abuts when raised, and beneath which it passes when in its lowered position. A helical spring 48 surrounding 110 the rod 42 and fast at one end to the bearing 44 and at the opposite end to a collar 49 on the rod 42 acts normally to rotate the rod 42 in the direction of the arrow on Fig. 5 allowing the latch 15 by gravity to 115 drop to a position where the flanged head 47 of the weft hammer will pass over the end of the latch as it vibrates forwardly, thus preventing actuation of the mechanism for initiating filling replenishment. The 120 positioning of the latch 15 into position to be struck by the weft hammer upon its forward vibration and thus to initiate filling replenishment is effected by the weft hammer itself. This result is secured by securing to the rod 42 a sleeve 50 provided with a crank arm 51 carrying at its free end a pin or bolt 52, and by pivotally mounting at 53 on the weft hammer a link 54 having a slot 55 engaging the pin 52. The action 125 130

65 The idea of the plurality of vertically disposed feeler points is, and the arrangement is such, that no matter what may be

is such that at each rearward vibration of the weft hammer this link acts to rock the rod 42 to raise the latch into position where if it remains it will be struck upon the forward vibration of the weft hammer.

During the normal operation of the loom the latch 15 is thus raised by the weft hammer upon each rearward vibration and as the weft hammer vibrates forwardly the 10 spring 48 rocks the rod 42 in the opposite direction allowing the latch to drop to its lower position. Thus while the latch is positioned at each rearward vibration of the weft hammer it does not remain in position 15 and so no initiation of filling replenishment takes place.

In this invention means are provided which are controlled by the feeler when in abnormal position to prevent movement of the 20 latch out of position for receiving its actuating movement from the weft hammer. A simple and effective construction for securing this result is illustrated. The dog 56 is pivoted to the feeler stand at 57 with 25 its nose 58 opposite the projections 36 on the feeler points when the feeler is in normal position. This dog is provided at its upper surface with a cam groove 59. The rod 42 above the dog has secured thereto by 30 means of the set screws 60 a collar 61 provided with a depending pin 62 having a preferably spherical lower end 63 riding in the cam groove 59.

During the normal operation of the loom 35 when the lay beats up with the shuttle boxed opposite the feeler and so long as the filling has not been replenished to the predetermined degree the filling on the bobbin contacting with the feeler points moves them 40 all forwardly against the action of their respective springs causing the projections 36 to pass forward of the nose 58 of the dog. Consequently the dog 56 is free to be rocked on its pivot 57 by the depending pin 45 62 from the shaft 52. When, however, the filling on the bobbin has become replenished sufficiently to uncover a groove or recess 38 in the bobbin opposite the feeler point, upon the next beat-up of the lay, one or more of 50 the feeler points will enter this recess and consequently the corresponding projections 36 will not be moved forwardly to clear the nose 58 of the dog, and the dog will be restrained from rocking movement on its 55 shaft. But when this restraint takes place the weft hammer 9 has by its rearward vibration raised the latch 15 into position so that when the weft hammer comes forwardly it will be actuated thereby. The 60 flange 47 on the weft hammer is now but a short distance in the rear of the free end of the latch 15 and as the weft hammer starts to vibrate forwardly the rod 42 is held from rotation under the influence of the spring 65 48 by the pin 62 locking in the cam groove

59 of the dog so that the rod 42 cannot rock to allow the latch 15 to drop before the free end of the latch is caught by the flange 47 on the weft hammer, and the latch 15 is moved forwardly rocking the controller rod 12 and initiating filling replenishment. The slot 55 in the link 54 enables the forward movement of the weft hammer to take place while the rod 42 is restrained against rotation.

The invention thus produces a construction which is simple and accurate in its operation and in which replenishment is promptly effected upon the exhaustion of the running filling to a predetermined amount.

Having thus described my invention what I claim as new and desire to secure by Letters Patent is—

1. An automatic filling replenishing loom 85 comprising a vibrating weft hammer, a feeler movable into abnormal position upon the detection of a predetermined degree of filling exhaustion on the running shuttle, a pivoted latch, means operated by bodily forward movement of the latch to initiate the filling replenishing action of the loom, a rod journaled for rotary movement on the loom frame and having a crank arm engaging the latch, a spring connected to the rod 90 and acting to rock the rod in a direction to allow the latch to move out of position to be struck by the weft hammer, a connection between said rod and the said weft hammer 95 and whereby the weft hammer upon its rearward vibration will rock the rod to move the latch into position to be struck by the weft hammer on its forward vibration, a dog pivoted adjacent the feeler and provided with a cam groove, and a pin projecting radially from the rod and engaging the said groove, the dog being free to rock under normal conditions but being restrained from rocking by the feeler when in abnormal position.

2. An automatic filling replenishing loom 110 having the construction defined in claim 1 in which there are a plurality of feelers movable into abnormal position and in which the dog is free to rock under normal conditions but is restrained from rocking by any 115 one of the feelers when in abnormal position.

3. An automatic filling replenishing loom comprising a vibrating weft hammer, a feeler stand, a feeler head mounted for yielding reciprocation in said stand, a plurality of superimposed ways in said head, a plurality of feeler fingers constituted as thin flat blades mounted in said ways, means for yieldingly and independently maintaining 120 said feeler fingers in projected position, the said feeler fingers independently movable into abnormal position upon the detection thereby of a predetermined degree of filling exhaustion on the running shuttle, a pivoted 125

130

latch, means operated by bodily forward movement of the latch to initiate the filling replenishing action of the loom, a rod journaled for rotary movement on the loom frame and having a crank arm engaging the latch, a spring connected to the rod and acting to rock the rod in a direction to allow the latch to move out of position to be struck by the weft hammer, a connection between 10 said rod and the said weft hammer whereby the weft hammer upon its rearward vibration will rock the rod to move the latch into position to be struck by the weft hammer on its forward vibration, and means for restraining the rocking of the rod upon the movement of any feeler finger into abnormal position.

4. An automatic filling replenishing loom comprising a feeler stand, a feeler head mounted for yielding reciprocation in said stand, a plurality of superimposed ways in said head, a plurality of feeler fingers constituted as thin flat blades mounted in said ways, means for yieldingly and independently maintaining said feeler fingers in projected position, and means for initiating filling replenishing action controlled by any one of the feeler fingers when in abnormal position due to the detection thereby of a predetermined degree of filling exhaustion 25 on the running shuttle.

In testimony whereof, I have signed my name to this specification.

ALONZO E. RHOADES.
